Primary Examiner — Susan Bennett Hattan*Assistant Examiner* — Marie Fast Horse(74) *Attorney, Agent, or Firm* — Thompson Coburn LLP(57) **CLAIM**

I claim the ornamental design for a the fan enclosure with grille, as shown and described.

DESCRIPTION

FIG. 1 is a front perspective view taken from the right top front corner of the fan enclosure with grille showing our new design;

FIG. 2 is a rear perspective view of fan enclosure with grille;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict environmental subject matter only and form no part of the claimed design.
